UNITED STATES PATENT OFFICE.

MAURICE WERNER, OF CHICAGO, ILLINOIS.

DESIGN FOR A RADIATOR.

42,793.

Specification for Design.

Patented July 9, 1912.

Application filed March 31, 1911. Serial No. 618,257. Term of patent 14 years.

To all whom it may concern:

Be it known that I, MAURICE WERNER, a citizen of the United States, residing at Chicago, in the county of Cook and State of Illinois, have invented a certain new, original, and ornamental Design for Radiators, of which the following is a specification.

Reference may be had to the accompanying drawing which is hereunto annexed, and is a part of the specification.

The figure is a front elevation of a radiator, showing my new design.

I claim:

The ornamental design for a radiator, as shown.

MAURICE WERNER.

Witnesses:

C. M. BAUMEISTER,
K. DOLBEY.
